UNITED STATES PATENT OFFICE.

JOEL B. HALL, OF HARRIMAN, TENNESSEE, ASSIGNOR TO JOHN B. RANSDELL, GIDEON HILL, AND MOSES W. EMERY, OF HARRIMAN, TENNESSEE, AND THOMAS DYE, OF LOGAN, KANSAS.

HAY-PRESS.

SPECIFICATION forming part of Letters Patent No. 746,078, dated December 8, 1903.

Application filed February 4, 1903. Serial No. 141,926. (No model.)

To all whom it may concern:

Be it known that I, JOEL B. HALL, a citizen of the United States, and a resident of Harriman, in the county of Roane and State 5 of Tennessee, have invented certain new and useful Improvements in Hay-Presses, of which the following is a specification.

The object of my invention is to produce a simple but effective press of this character 10 wherein all possible lost motion is taken up and the full force and effect of the power exerted; and with this and minor objects in view my invention consists of the parts and combination of parts, as will be hereinafter more 15 fully set out.

In the drawings, Figure 1 is a side elevation of the press embodying my invention. Fig. 2 is a top plan of the same.

1 represents the main sides of the frame, set 20 upon subsills 2. The forward portion of the frame is provided with any approved type of baling-box having the usual braces 4.

5 is the opening through which the hay is supplied to the press.

25 6 represents bars carrying the usual baling-dogs on the inside of the press, said dogs not being shown. Said bars are mounted upon rods 7, provided with cap-nuts 8, between which and said bars is interposed the coil-spring 9, whereby said rods and the dogs carried thereby are given a resilient mounting.

10 represents cross-timbers extending from the side timbers 1 and connecting said side timbers.

35 11 represents torsional braces, the ends of which are anchored to the cross-timbers 10.

12 is a loop, the free ends of which are secured to the forward ends of the torsional braces 11.

40 13 is a brace, the ends of which are secured to the side of the baling-chamber, while its middle portion is extended in the form of a loop toward the torsional braces 11, the loop of this brace 13 being connected to the loop 45 or brace 12 by means of a bolt 14.

15 is a shaft mounted in one corner of the frame, upon which is secured a double cam 16, the straight faces of which, while on opposite sides of the axis of the cam, are parallel with each other. Above the cam on the

shaft 15 is mounted a ratchet-wheel 17, above which, on the same shaft, is loosely mounted a sweep 18, said sweep being provided with a spring-dog 19, adapted to engage the ratchet-wheel 17. 55

20 is the lead-bar, secured to the sweep.

21 is a plunger to which a pitman 22 is suitably pivoted, the rear end of the pitman being deflected to one side, as at 23, at its extreme rear end, and provided with an antifriction-roller 24, constructed for engagement with the cam 16. Said pitman is provided with a guard 25, the object of which is to prevent the roller 24 from becoming locked in the lowermost point of the cam. 65

26 is a link pivoted to the corner of the frame diametrically opposite the corner to which the cam 16 is secured, the forward end of said link being pivoted to the free end of the pitman-rod 22, as more clearly shown in Fig. 2, thereby forming in connection with rod 22 a toggle-lever, which folds or closes in a direction toward the axis of the cam 16. 70

27 is a coil-spring, one end of which is secured to the side of the frame opposite that to which the link 26 is pivoted, while the other end is secured, by means of a bolt 28, to the plunger or pitman-rod 22. 75

The operation of the device is as follows: In the normal position of the parts the plunger 80 of course is retracted back of the opening 5, thus positioning the antifriction-roller 24 at the lowest point of the cam. Power being applied to the sweep 18, the antifriction-roller begins to ascend the short curved face of the cam, whereupon power is exerted directly upon the rod 22; but as soon as the antifriction-roller is in engagement with the long curved face of the cam the link 26 is brought into play, thereby bringing into effect the forces of the toggle-lever, and this toggle-lever is of such construction that it may be extended its full length—that is to say, it may be brought for all practical purposes to a dead-center, whereby all of the effective power 85 of such a lever is exerted upon the plunger in the baling-box. As soon as the antifriction-roller 24 is about to leave the long curved face of the cam the coil-spring 27 immediately retracts the plunger and by reason of its 90 95 100

position with reference to the link 26 folds or retracts the toggle-lever until the anti-friction-roller is at the lowest point on one of the straight faces of the cam, the guard 25 5 preventing the antifriction-roller from being locked between the straight and the short curved faces of the cam.

It will be readily seen by those skilled in the art that by reason of the relative positions 10 of the cam, the link 26, and the spring 27 I am enabled to secure the full force and effect of these several elements.

Having thus described my invention, the following is what I claim as new therein and 15 desire to secure by Letters Patent:

1. In a hay-press, the combination with the baling-box, a brace secured on each side thereof and extending beyond the box, crossed braces secured to the frame of the press at one 20 end, a substantially V-shaped brace connecting one end of each of said crossed braces and adjustable means connecting said V-shaped brace with the brace secured to the baling-box, of a plunger, a link pivoted at one end 25 to one of said crossed braces and at its other

end to the plunger, a cam pivoted to one end of the other crossed brace and a spring connecting the plunger and frame of the press.

2. In a hay-press, the combination with a double cam secured to one side of the frame, 30 a sweep to operate said cam and slip-joint between said cam and its sweep, of a link pivoted to the side of the frame opposite to that to which the cam is pivoted, a plunger one end of which is deflected and provided 35 with an antifriction-roller for engagement with said cam, said plunger being pivotally secured to said link and a coiled spring, one end of which is secured to the plunger, while the other end is secured to the side of the 40 frame opposite that to which the link is pivoted, and a guard secured to one side of the plunger near its deflected end.

The foregoing specification signed this 5th day of January, 1903.

JOEL B. HALL.
